BOTTLE

Roy W. Dike, Wheeling, W. Va., assignor to Continental Can Company, Inc., New York, N.Y., a corporation of New York

Application January 16, 1959, Serial No. 54,196

Term of patent 14 years

(CL D58—6)

Figures 2, 3, 4, 5 and 6 are diagrammatic horizontal sectional views taken respectively on the lines 2—2, 3—3, 4—4, 5—5 and 6—6 and showing the horizontal sectional contour of the bottle at the several planes on which the respective views are taken.

I claim:

The ornamental design for a bottle, as shown.
